COUNTING APPARATUS

Henry E. Greenhow, Chingford, London, England, assignor to English Numbering Machines Limited, Enfield, Middlesex, England

Application February 14, 1958, Serial No. 715,371

Claims priority, application Great Britain
December 9, 1957

4 Claims. (Cl. 235—131)

This invention relates to counting apparatus.

It is an object of the invention to provide an improved counting apparatus wherein a unit number wheel, which carries the lowest order of digits, wholly or partly encompasses a mechanism for driving the counting apparatus.

It is another object of the invention to provide a driving mechanism permitting a counting apparatus to be operated at high speeds while eliminating the danger of double counting or of the unit number wheel being advanced a plurality of units instead of a single unit on each count. It is a further object of the invention to eliminate variations in the performance of a counting apparatus due to variations in spring tensioning.

Most forms of counting apparatus in which the unit number wheel wholly or partly encompasses the driving mechanism comprise a drive-plate affixed to a driving spindle and carrying one or more spring-loaded driving pawls as well as a stationary plate carrying one or more spring-loaded detent pawls by which the unit number wheel is located in position when the driving shaft is stationary. In such counting apparatus, the inside of the unit number wheel is slotted axially to provide ratchet teeth. The leading edges of these slots are sharply angled to provide engagement for the driving and detent pawls, while the trailing edges have a more gradual slope so that the detent pawls can readily disengage from the slots while the wheel is rotating. It is sometimes difficult with such a mechanism to count at high speed because the momentum imparted to the unit number wheel may carry it past its appropriate locating points. The driving pawls may also be disengaged entirely from the internal slots of the unit number wheel if the driving mechanism is subjected to excessive shock. In either case, the counter reading may be inaccurate.

Accordingly, it is still another object to provide a counting apparatus in which these shortcomings have been removed.

The tensioning of the pawl springs is sometimes increased to overcome such miscounting, but this leads to a higher operating torque being required, greater wear between the pawls and the ratchet teeth, and consequently to a harsh action. The performance and cost of counting apparatus incorporating such ratchet mechanisms is also affected by the accuracy and consistency of the springs used.

It is still a further object to provide a counting apparatus which is insensitive to variations in the springs used.

It is yet another object of the invention to provide a counting apparatus the driving mechanism of which is not dependent on the use of individual detent pawls.

It is yet a further object of the invention to provide a counting apparatus requiring a relatively low operating torque but at the same time providing a reliable and positive counting operation.

It is still another object of the invention to provide a counting apparatus of simple construction and capable of being quickly and easily assembled.

These and other objects and advantages of the inven-

2

tion will become apparent to those skilled in the art from the following description when read in conjunction with the accompanying drawings, which by way of example illustrate a specific embodiment of the invention and in which:

Fig. 1 is an elevational view, partly in section and partly broken away of a counting apparatus having a ratchet mechanism;

Fig. 2 is an elevational view, partly in section and partly broken away showing the ratchet mechanism of the apparatus of Fig. 1 in a position corresponding to the start or finish of a cycle of operation;

Fig. 3 is a view, corresponding to Fig. 2, but showing the ratchet mechanism in a position just before the end of a ratchet operation stroke;

Fig. 4 is a view similar to Fig. 3, but showing the ratchet mechanism in a position just before the end of a ratchet return stroke; and

Fig. 5 is a perspective view of the counting apparatus. A unit number wheel 1 carries numbers about its outer periphery and has a counterbore with equally spaced axial slots 2. To an extension member 8 of a casing 3 is fixed a stationary first ratchet wheel 4 on the front face of which are cut equally spaced ratchet teeth 5. Mating with the stationary ratchet wheel 4 is an intermediate, second, ratchet wheel 6 having projections 7 on its periphery so shaped and disposed as to be a sliding fit in the axial slots 2 in number wheel 1. Across both faces of the intermediate ratchet wheel 6 there are provided sets of equally spaced ratchet teeth 11 and 12, one set of teeth 11 mating with the teeth 5 on the stationary ratchet wheel 4 and the other set of teeth 12 mating with equally spaced ratchet teeth 13 provided on one face of a driving, third, ratchet wheel 14. The driving ratchet wheel 14 has a hub 15 acting as a bearing for the intermediate ratchet wheel 5. A driving spindle 16, is held against axial movement in both directions by retaining clips 24 which engage in grooves 25 provided in the spindle 16. The spindle 16 is fitted with a pin 17 which locates in a slot-like recess 18 extending from the bore of the driving ratchet wheel 14. The open end of the casing 3 is sealed by a coverplate 21 and the width of the gap 23 between the inside face of the coverplate 21 and the rear of the driving ratchet wheel 14 is so arranged as to be slightly greater than the depth of each ratchet tooth, and appreciably less than twice the depth of one ratchet tooth. In this gap, but so arranged as not to reduce its effective width, is fitted a spring 22 which urges the teeth on the three ratchet wheels into mutual engagement. The counting mechanism is fitted with two stops 26 provided on the case 3, only one of the stops 26 being visible in Fig. 1, the stops cooperating with a pin 30 inserted in the spindle 16 so as to restrict the movement of the spindle to an arc of 36° plus a working clearance. A spring 31 is provided for returning the spindle 16 to its initial position after each operation thereof. By omitting the stops 26 and 27, the pin 30, and spring 31, the counting mechanism may be used for continuous rotary movement with each digit position indexed by the ratchet mechanism.

Any rotational movement of the driving spindle 16 is transmitted through the pin 17 to the driving ratchet wheel 14 whose teeth 13 engage on the intermediate ratchet wheel 6, thus imparting rotary movement to the unit number wheel 1 through the peripheral projections 7 on the intermediate ratchet wheel 6. During rotational movement of the driving spindle 16, the teeth 11 on the intermediate ratchet wheel 6 slide up the slope of mating teeth 5 on the stationary ratchet wheel 4 thus imparting axial motion to the intermediate ratchet wheel 6 and the driving ratchet wheel 14 equal to the depth of one ratchet tooth, as permitted by the connection between the driv-

ing spindle 16 and the driving ratchet wheel 14 to the extent of the clearance between the coverplate 21 and the rear of the driving ratchet wheel 14. At the end of the rotational movement of the driving spindle 16, the ratchet teeth are forced into mesh again under the tension of the spring 22 which urges the three ratchet wheels into mutual engagement.

The driving spindle 16 may be rotated in the opposite direction to return to its initial position, under tension of the spring 31 of sufficient power to overcome the tension of the spring 22. However, if desired, the spring 31 can be omitted, the return of the spindle 16 being effected by external mechanical means. During the return movement, the intermediate ratchet wheel 6 is prevented from rotating by the mating teeth 5 on the stationary ratchet wheel 4. The driving ratchet wheel 14 is rotatably connected to the driving spindle 16 by the pin 17 and its ratchet teeth 13 slide up the slope of the mating teeth 12 on the intermediate ratchet wheel 6 until the initial position of the driving spindle 16 is reached when the teeth 13 and 12 of the driving ratchet wheel 14 and the intermediate ratchet wheel 6 respectively are forced into mesh again under the pressure of the spring 22.

It will be seen that for the unit number wheel 1 to overtravel, it is necessary for the intermediate ratchet wheel 6 to rotate beyond the motion imparted to it by the driving ratchet wheel 14. The teeth on the intermediate ratchet wheel 6 would then have to slide simultaneously over the crests of the teeth on both the driving ratchet wheel 14 and the stationary ratchet wheel 4, thus imparting an axial motion to the driving ratchet wheel 14 equal to at least twice the depth of one ratchet tooth. Since this distance is in excess of the gap 23 provided, the intermediate ratchet wheel 6 would be locked axially between the stationary ratchet wheel 4 and the driving ratchet wheel 14 before it had rotated through 72°. Any momentum separately imparted to the intermediate ratchet wheel 4 and the unit number wheel 1 is thus eliminated before overtravel causing double counting has taken place.

It should be clearly understood that the embodiment described and illustrated is given by way of example only. Many modifications, omissions and additions are possible without departing from the spirit of the invention.

I claim:

1. A counting apparatus comprising a stationary ratchet wheel, radial teeth cut across the front face of said stationary ratchet wheel, an intermediate ratchet wheel, radial teeth cut across both faces of said intermediate ratchet wheel with the teeth on one face directionally opposed to the teeth on the other face (when looking at the respective face), a driving ratchet wheel, radial teeth on said driving ratchet wheel and similar but directionally opposed to those on the stationary ratchet wheel, a hub on said driving ratchet wheel, said hub carrying said intermediate ratchet wheel, a driving spindle, a pin carried by said driving spindle, said pin engaging a slot in a bore of the driving ratchet wheel so that the driving ratchet wheel rotates with the driving spindle but is allowed to move axially along the spindle, means for securing the said spindle against axial movement, a single

spring exerting pressure on the driving ratchet wheel towards the stationary ratchet wheel for urging the ratchet teeth on the driving ratchet wheel, the intermediate ratchet wheel and stationary ratchet wheel into mutual engagement, an outer barrel-shaped unit number wheel having at least one axial slot therein, and at least one projection on the intermediate ratchet wheel and disposed about its periphery to provide locations for and ensure a sliding fit with said axial slot.

2. A counting apparatus comprising a stationary ratchet wheel, radial teeth cut across a front face of said stationary ratchet wheel, an intermediate ratchet wheel adjacent said front face, radial teeth cut across both faces of said intermediate ratchet wheel with the teeth on one face directionally opposed to the teeth on the other face (when looking at the respective face), a driving ratchet wheel, radial teeth on a face of said driving ratchet wheel adjacent said intermediate ratchet wheel, said radial teeth on said driving ratchet wheel being similar but directionally opposed to those on the stationary ratchet wheel, a driving spindle co-axially carrying said stationary, intermediate and driving ratchet wheels, means connecting said driving ratchet wheel to said spindle so that the driving ratchet wheel is rotatable with, but axially displaceable relatively to said spindle, means for securing said spindle against axial movement relatively to said stationary ratchet wheel, spring means exerting pressure on said driving ratchet wheel in the direction towards said stationary ratchet wheel for urging adjacent ratchet teeth on said driving ratchet wheel, said intermediate ratchet wheel and said stationary ratchet wheel into mutual engagement, a unit number wheel, an outer rim forming a part of said number wheel and surrounding at least in part all of said ratchet wheels coaxially, and means connecting said number wheel to said intermediate ratchet wheel so that said number wheel is rotatable with said intermediate ratchet wheel and said intermediate ratchet wheel is axially displaceable relatively to said number wheel.
3. A counting apparatus as claimed in claim 2, further including an abutment cooperating with said driving ratchet wheel and arranged at a distance therefrom which is greater than the depth of each ratchet tooth of said driving ratchet wheel but less than twice such depth for preventing overtravel leading to double counting of said unit number wheel by said driving ratchet wheel abutting against said abutment.

4. A counting apparatus as claimed in claim 3, including a casing, and a cover plate on said casing, said abutment being formed by said cover plate, said spring means being located between said cover plate and said driving ratchet wheel and bearing against said cover plate and said driving ratchet wheel.
